UNITED STATES PATENT OFFICE.

MYRON DINGS, OF MILWAUKEE, WISCONSIN.

MAGNETIC SEPARATOR.

No. 821,615.

Specification of Letters Patent.

Patented May 29, 1906.

Application filed September 15, 1904. Serial No. 224,519.

To all whom it may concern:

Be it known that I, MYRON DINGS, a citizen of the United States, residing at Milwaukee, county of Milwaukee, and State of Wisconsin, have invented new and useful Improvements in Magnetic Separators, of which the following is a specification.

My invention relates to improvements in magnetic separators.

The objects of my invention are, first, to provide means for passing the material directly through a magnetic field and subjecting the material to a magnetic pull of increasing intensity during its passage, the material being retarded during its passage in order to facilitate its magnetization; second, to provide for the removal of the magnetized material by an air-brush of sufficient strength to overcome the residual magnetism; third, to provide a balanced carrier capable of being moved into and out of a magnetic field without side pull in the supporting-bearings.

In the following description reference is had to the accompanying drawings, in which—

25 Figure 1 is a vertical sectional view of my invention drawn through the axes of the magnets. Fig. 2 is a cross-sectional view drawn on line $z-z$ of Fig. 1. Fig. 3 is a vertical sectional view drawn on the axes of the 30 magnetic chutes, showing the suction-tubes and with the distributing-cone removed. Fig. 4 is a sectional view drawn on line $y-y$ of Fig. 3. Fig. 5 is a plan view of the distributing-cone.

35 Like parts are identified by the same reference characters throughout the several views.

A vertical non-magnetic shaft 1 is provided with radial non-magnetic arms 2, which support a ring carrier 3, made up of a series of 40 magnetizable segments a , separated by non-magnetic material b . The shaft is driven from any suitable source of power through a driving-shaft c and gears d and e . Electromagnets 5 are located symmetrically around the shaft 1 and are provided with upper pole-pieces 6, which have curved margins thickened vertically at 7 to diminish the magnetic resistance of the air-gap between the polar margins 7 and the ring carrier 3, which revolves in close proximity to these margins. The pole-pieces 6 of the several magnets may consist of a single plate of metal having a central aperture for the shaft 1 and extending outwardly therefrom in the form of radially-widened wings over the respective magnets. The lower pole-pieces 8 are similarly formed,

but extend outwardly farther from the shaft and are provided with upwardly-projecting marginal flanges 9, the upper edges of which are so located that the magnetic circuit between them and the polar margins 7 of the upper pole-pieces will extend through the interposed segments of the ring carrier 3.

The material is fed from a hopper 10 to a distributing-cone 11, and the latter is provided with flanges 12, whereby the material is confined to those portions of the cone which cover the pole-pieces 6. Inwardly-inclined non-magnetic deflecting-shields 13 receive the material from the cone and direct it through the magnetic field between the ring carrier 3 and the upper edges of the respective marginal flanges 9 of the lower pole-pieces into the segmental chutes 15. The latter extend downwardly and discharge the non-magnetic material into suitable receptacles 16, these chutes being preferably tapered and extended through holes in the lower pole-pieces 8. The magnetite or magnetizable material is taken up by the ring carrier 3, which conveys it in a circular path out of the magnetic field when the segments of the carrier become de-energized successively and deposit the magnetite in chutes 18 between the pole-pieces of one magnet and those of another. 85 The chutes 18 are provided with flanges 19, which extend upwardly in close proximity to the ring carrier 3, and an air-current through this narrow space serves to detach the magnetite from the ring if held thereto by residual magnetism. This current may be produced by a suction-fan 21, which draws the air from a receiving-box 22, into which the chutes 18 discharge. The box is provided with a slide 23, covering an aperture in its bottom, so that 90 by withdrawing the slide the contents of the box 22 may be discharged from time to time into a chamber 25.

Referring to Fig. 1, it will be seen that the ring 3 is provided with a series of annular 100 ribs 27 on its outer surface, the upper rib having the largest diameter and the others being successively smaller in diameter, thus forming magnetic zones in the gap through which the material passes. The deflecting-shields 13 are preferably formed with counterpart ribs 28, so that the surface of the shield alternately approaches and recedes from the surface of the ring 3 and each of the ribs 28 below the top one is located nearer to 105 the opposing rib 27 on the ring than the one above it. The ribs 28 are preferably ar-

ranged in the form of steps which successively bring the material into closer proximity to the ring 3. With this arrangement the strongly magnetic material is withdrawn by the upper ribs of the ring, thus giving the material of slight magnetic susceptibility the strongest field and greatest freedom from entanglement. The step form of the shield 13 retards the material between the ribs sufficiently to overcome the magnetic lag and permits the material to accumulate between the ribs, and this also retards the flow of the material passing over it with better results than can be secured where the material slides along a smooth metallic surface.

In the drawings I have shown but two electromagnets. The desirable number depends upon the size of the machine. In any case they should be disposed symmetrically around the shaft-axis to balance the magnetic pull.

It will be observed that the deflecting shields 13 are connected with a suitable wall or frame-piece 30 by bars 31, which are bolted to the frame-piece. The bars 31 are offset at their upper ends and are connected with adjusting-screws, to which they are secured by suitable nuts, as shown, whereby the shield may be raised or lowered into greater or less proximity to the carrier.

Having thus described my invention, what I claim as new, and desire to secure by Letters Patent, is—

1. In a magnetic separator, the combination of a rotary magnetizable carrier; opposing segmental pieces disposed in sets with pieces of opposite polarity in each set on opposite sides of the carrier, and said sets being symmetrically arranged with reference to the carrier to balance the magnetic pull thereon; segmental non-magnetic shields extending between the carrier and one pole-piece of each set, and means for distributing material to said shields.

2. In a magnetic separator, the combination of an upwardly-extending driving-shaft; a non-magnetic support mounted to rotate with said shaft; a magnetizable ring connected with said support; a set of magnets, arranged with cores parallel to the shaft at a less radius than that of said ring; segmental upper pole-pieces symmetrically balanced, and extending outwardly into close proximity to the inner faces of said ring; segmental lower pole-pieces of opposite polarity extending outwardly and upwardly into proximity to the outer faces of said ring; inclined non-magnetic shields extending downwardly and inwardly between said pole-pieces; and chutes extending from the lower ends of the shields downwardly through suitable apertures in the lower pole-pieces.

3. In a magnetic separator, the combination of an upwardly-extending driving-shaft; a non-magnetic support mounted to rotate

with said shaft; a magnetizable ring connected with said support; a set of magnets, arranged with cores parallel to the shaft at a less radius than that of said ring; segmental upper pole-pieces symmetrically balanced and extending outwardly into close proximity to the inner faces of said ring; segmental lower pole-pieces of opposite polarity extending outwardly and upwardly in proximity to the outer faces of said ring; inclined non-magnetic shields extending downwardly and inwardly between said pole-pieces; and chutes extending from the lower ends of the shields downwardly through suitable apertures in the lower pole-pieces; the opposing faces of said shield and ring being provided with ribs having opposing edges in close proximity, whereby magnetic zones of alternating greater and less intensity are produced.

4. In a magnetic separator, the combination of opposing segmental pole-pieces; a magnetizable carrier-ring arranged to travel between the pole-pieces; and a shield extending downwardly and inwardly between said ring and one of the pole-pieces; the opposing faces of the shield and ring being ribbed and arranged to approach and recede in zones parallel to that of ring rotation, whereby narrow magnetic zones of great intensity are provided with minimum liability of clogging.

5. In a magnetic separator, the combination of opposing segmental pole-pieces; a magnetizable carrier arranged to travel between the pole-pieces, and provided with a downwardly and inwardly receding series of annular ribs; a segmental shield arranged to extend downwardly and inwardly between the carrier and one of the pole-pieces, and adapted to convey material along the under surfaces of the overhanging carrier-ribs.

6. In a magnetic separator, the combination of opposing segmental pole-pieces; a magnetizable carrier arranged to travel between the pole-pieces, and provided with a downwardly and inwardly receding series of annular ribs; a segmental shield arranged to extend downwardly and inwardly between the carrier and one of the pole-pieces, and adapted to convey material along the under surfaces of the overhanging carrier-ribs, said shield being supported by vertically-adjustable hangers.

7. In a magnetic separator, the combination of an upwardly-extending shaft; a carrier supported to rotate therewith, and provided with an annular series of magnetizable segments; magnets arranged with their axes extending parallel to the shaft, and provided with stationary segmental pole-pieces extended to opposite sides of the path of said segments, and with pieces of like polarity extended in opposite directions; a segmental cone arranged above the magnets and with its apex above the shaft and adapted to deliver material into the magnetic zones formed by said

pole-pieces; said pole-pieces being symmetrically arranged with reference to the shaft, whereby the magnetic pull upon said ring is balanced.

- 5 8. In a magnetic separator, the combination of a rotary magnetizable carrier; opposing segmental magnetic pole-pieces disposed in sets, with pieces of opposite polarity in each set on opposite sides of the carrier and 10 symmetrically arranged in reference to the carrier to balance the magnetic pull thereon; segmental non-magnetic shields extending between the carrier and one pole-piece of each set; and means for distributing matter to 15 said shields; intermediate shields between the sets of pole-pieces disposed along and

adjacent to the outer face of the carrier; and chutes composed of annular walls extending downwardly from said shields and subdivided segmentally, some of said chutes being 20 arranged to lead downwardly through the lower pole-pieces, and other of said chutes being arranged to lead downwardly between the pole-pieces and a suction-chamber connected with the lower ends of said last-mentioned 25 chutes.

In testimony whereof I affix my signature in the presence of two witnesses.
